GEAR LAPPING MACHINE

Ernest A. Overstedt, Detroit, Mich., assignor, by
mesne assignments, to Michigan Tool Com-
pany, a corporation of Delaware

Application August 7, 1933, Serial No. 683,979

11 Claims. (Cl. 51—26)

My invention relates to machines and particularly to a machine for accurately finishing the teeth of a gear after they have been machined to substantial form to true the gear teeth to 5 accurate predetermined dimension.

Efforts have been made heretofore to accurately finish gear teeth by employing a suitable lapping tool and compound when operating in mesh with the gear by a method clearly illustrated in the 10 G. C. Carhart Patent No. 1,537,583, dated May 12, 1925, and assigned to the assignee of the present invention. The present invention relates primarily to a new form of machine and method, extending the principles disclosed in the Carhart 15 patent.

It is well known, that when operating gears in mesh with each other in the presence of a lapping compound therebetween, unsatisfactory machining is effected because of the fact that no abrading 20 is produced on the pitch line of the teeth as no slippage occurs between the surfaces of the mated teeth at this point. The Carhart patent had solved this problem in a simple manner by offsetting a spiral gear on a spur lap or a spur gear 25 on a spiral lap so as to effect a lateral slippage therebetween which machines an equal amount at all points from the crown, through the pitch line, to the root of the teeth.

The present machine utilizes this offset principle for effecting a lateral slippage between the 30 lap and gear and utilizes a plurality of the laps which are driven by the gear to be machined in the presence of brake pressure which may be regulated relative to the kind of gear and quality 35 of the work to be produced.

The laps are mounted so as to be adjustable angularly to mate with any type of spur or spiral gear and to be offset further therefrom when desirable. That is to say, when employing three 40 laps, have one set at one angle and the other set at another angle slightly different from that of the angle of the lead of the gear so as to produce a slope to the edges of the gear teeth which is so desirable on gears moved longitudinally into mesh 45 with each other. This slight relief on the side edges of the teeth permits the ready meshing of one gear relative to another and produces quiet shifting of transmission gears which are shifted axially. The machine is constructed to drive the gear to be lapped a predetermined number of 50 times in one direction and automatically shifting and repeating the operation in the opposite direction and further repeating the cycle if necessary and thereafter stopping the machine. One of 55 the lapping tools is mounted on a head which is

movable upwardly to permit the gear to be removed from the centers which support the gear in rotation and to permit a new gear to be inserted. Upon pulling the lever the lap is moved down into engagement with the gear, applying a 5 pressure through the gear to the other laps to retain them in intimate relation with the gear.

Accordingly, the main objects of my invention are to provide a gear finishing machine with a plurality of tools which may be mated with a gear 10 and which are driven by the gear against a brake pressure; to provide laps which are of the spiral type when a spur gear is to be machined or spur laps when a spiral gear is to be machined as the case may be; to offsetting the laps so that the 15 teeth thereof mate with the teeth of the gear so as to effect a lateral slippage between the sides of the teeth of the laps and those of the gear which will machine uniformly from the crown to the root of the gear teeth; to further offset one or more of 20 the laps to machine a relief on the side edges of the gear teeth; to mount the laps for angular movement so that they may be offset at an angle an amount conforming to the lead of the teeth of the gear when spiral gears are to be machined or 25 to the lead of the teeth of the lap when a spur gear is to be machined or to be further offset in relation thereto when a relief at the ends of the teeth is to be machined; to provide movable means 30 for supporting one of the laps for raising the lap out of contact with the gear to permit the gear to be removed and a new gear inserted in the machine and thereafter for moving the lap into engagement with the gear to apply a pressure between the plurality of laps and the gear during 35 the machining operation; to provide automatic means for operating the gear and laps a predetermined number of times in one direction and then in a reverse direction or in repeated cycle thereof 40 as is desirable; to provide automatic means for stopping the machine after any such cycle of movement; and, in general, to provide a machine which is simple in operation and adjustment and which is universal in application. 45

Other objects and features of my invention will be either specifically pointed out or will become apparent when referring, for a better understanding of my invention, to the following description taken in conjunction with the accompanying drawings, wherein:

Figure 1 is a perspective view of a finishing machine embodying features of my invention,

Fig. 2 is a side view of the machine illustrated in Fig. 1, with the motor omitted therefrom, 55

Fig. 3 is a front view of the structure illustrated in Fig. 2, with the motor mounted in position.

Fig. 4 is an enlarged front view, in elevation, of the gear box of the machine illustrated in Fig. 3, with the front broken away.

Fig. 5 is an enlarged sectional view of the structure illustrated in Fig. 4 taken on the line 5—5 thereof.

Fig. 6 is a sectional view of the structure illustrated in Fig. 4, taken on the line 6—6 thereof.

Fig. 7 is a sectional view of the structure illustrated in Fig. 6, taken on the line 7—7 thereof.

Fig. 8 is a sectional view of the structure illustrated in Fig. 6, taken on the line 8—8 thereof.

Fig. 9 is an enlarged sectional view of the structure illustrated in Fig. 4, taken on the line 9—9 thereof, and

Fig. 10 is an enlarged sectional view of the structure illustrated in Fig. 3, taken on the line 10—10 thereof.

Referring to Figs. 1, 2 and 3, I have illustrated a machine bed 11 consisting of a table supporting portion 12 which is at right angles to yoke supporting portions 13 and 14 upon which a yoke 15 of inverted U-shape is supported and secured by bolts 16. Suitable ways 17 are provided on the top of the table supporting portion 12 upon which a table 18 is disposed for horizontal reciprocal movement. Upon the table is mounted a fixed head stock 19 and a tail stock 21 which is adjustable on the table in spaced relation to the head stock. The head stock 19 is provided with a fixed center 22 having a revolvable gear 61 thereabout which causes the work to be rotated. The adjustable tail stock is provided with a center 23 which is adjustable relative to the tail stock for clamping the work between the centers.

I have illustrated a spiral gear 24 mounted between the centers and mated with a plurality of lapping tools 25 which are similar in construction, although it is within the purview of my invention to employ tools of different diameters or with modified tooth forms so as to provide different pressure angles relative to the pressure angles of the gear teeth. The tools 25 are mounted on arbors 26 which are attached to a brake mechanism (not shown) which is supported in a cylinder 27 mounted on an adjustable arm 28. The brake mechanism is so constructed, in the nature of veins or gears, as to operate a fluid provided in the reservoir within the cylinder to build up a pressure which may be adjusted through the regulation of the size of the orifice, to thereby apply a braking force to the arbors to produce a predetermined load on the teeth of the tools and gear.

A balance brake is preferably provided, that is to say, a brake operable about the periphery of the arbor to balance the force thereof to prevent the application of a pressure on one side of the arbor which would wear the bearing thereof an unequal amount. The brake is so constructed as to operate in both directions through the flow of fluid caused either by the veins or the gears, during either direction of movement of the arbor. The adjustment of the orifice is effected through the adjustment of the element 29 and the amount of pressure is registered on a gauge 31 which is connected within the cylinder.

A suitable scale 32 may be provided on the extension of the cylinder and arm, for indexing the arbor relative to the degree of angular offset relation of the lapping tool relative to the gear teeth, while suitable ways 33 are provided for supporting the arm to radially adjust the tools

relative to the work. A suitable indexing scale may be provided on the arm relative to the yoke 15 or otherwise, for indexing the setting of the arm to have the tools disposed on a predetermined radius conforming to the radius of the gear to be lapped. A suitable lead screw 34 is provided for moving the arm on the ways by operating a suitable handle engaging the stub arbor 35 in extension of the lead screw and the radially disposed lands 36 thereof in the nature of a modified spanner wrench 37, as illustrated on the top of the machine, for adjusting the topmost tool relative to its support.

In this manner, all the lapping tools may be adjusted radially to converge upon the gear to be machined and at the same time adjusted angularly to a degree conforming to that of the teeth or slightly therefrom for a purpose referred to hereinbefore and which will be referred to hereinafter. A suitable indexing plug 38 may be provided in conjunction with the extending indexing scale 32 for checking the index in a well known manner.

On the upper part of the yoke 15 ways 41 are provided in which a brake mechanism and a tool are supported by means of a toggle link connection 42 operated by a handle 43 against a spring 44 which biases the tool upwardly. The toggle link 42 is illustrated as being in on center position and it is only necessary to push the handle 43 upwardly to brake the toggle and permit the tool to be moved upwardly to clear the gear 24 so that the longitudinally movable center 23 may be moved out of engagement with the shaft upon which the gear is mounted to permit the gear to be removed from the machine and a second gear to be inserted in its stead. Through the downward movement of the handle 43 the tool is moved into engagement with the gear which is already in engagement with the other two laps to apply a predetermined pressure thereto. Through the movement of the toggle 42 into center or aligned position, the handle 43 is retained in a downward position to maintain such pressure on the gear.

For effecting the longitudinal movement of the center 22, I have provided a handle 46 operating a gear sector 47 in engagement with rack-like teeth 48 provided on a spindle 49 in which the center 23 is mounted in fixed relation to cause the spindle 49 and therefore the center 23 to be moved longitudinally toward or away from the center 22, as illustrated more clearly in Fig. 2. Through the counter-clockwise rotation of the handle 46 the spindle 49 and therefore the center 23 is moved to the left, as viewed in Fig. 2, to clamp the shaft of the gear between the centers, after which a handle 51 may be tightened to clamp the spindle and therefore the center in fixed engaged relation.

In Fig. 10, I have illustrated the method of driving the shaft and the gear 24 through the rotation of the gear 61 about the center 22 effected through the rotation of a shaft 52 driven by a suitable belt 53 off of a pulley 54 which is rotatably mounted in a bearing 55 on an arm 56 secured to the yoke 15 of the machine. The shaft 52 has a spline-way 57, as illustrated in Fig. 2, to permit the shaft to slide through the rotatable pulley during the time it is driven thereby. The shaft 52 is supported in suitable bearings 58 and has a gear 59 secured to its forward end in engagement with a gear 61 for rotating the gear 61 about the center 22.

The gear 61 is provided with a pin or dog 60

which extends outwardly therefrom to be revolved about the center 22 which engages a dog or pin on the shaft to cause the shaft to rotate about the centers 22 and 23. A suitable bearing 62 is provided between the head of the spindle 63 which supports the center 22 and the gear 61 to eliminate friction therebetween. As the table 18 is reciprocated backwardly and forwardly upon the ways 17 the shaft 52 moves through the rotating pulley 54 to effect the operation of the gear 59 and therefore the gear 61. In this manner the pin 60 on the gear 61 is rotated to drive the shaft about the centers 22 and 23.

A motor 65 illustrated in Figs. 1 and 3, is mounted on one end of the base frame 11 having a pulley thereon which is connected by a belt 66 to a pulley 67 mounted on a shaft 68. The shaft 68 effects the reciprocation of the table, the reversal of the tools and the operation of suitable controls for actuating the reversing elements and for stopping the machine after a predetermined cycle of operation. The shaft 68, as viewed in Fig. 6, drives a gear 69 for operating through a gear 71, a shaft 72 which drives through a belt and pulley connection 73, a reversing and stop mechanism 74 which will be described more fully hereinafter.

The shaft 72 is provided with a gear 70 on its outer end which is connected with a gear 75, as illustrated in Fig. 4, for driving a shaft 76 and a beveled pinion 77 which is secured thereto for driving a ring gear 78 controlling the operation of the reciprocating mechanism 79 which will be described more fully hereinafter.

The shaft 68 also drives a gear 81 which is in mesh with an idling gear 82 meshed with a gear 83 which is fixed to a shaft 84 for driving the shaft 84 in one direction when a clutch 85 connects the gear 81 to the shaft 68. An additional gear 86 is connected to the opposite end of the shaft 68 which, as illustrated in Fig. 8, is in mesh with a gear 87 also on the shaft 84 for operating the shaft in an opposite direction when a clutch 88 connects the gear 86 to the shaft. The shaft 84 is provided with a gear 89 on its outer end which meshes with a gear 90 on shaft 80 which extends through the base of the machine to drive a pulley 91 on the opposite side of the machine and to which the belt 53 is connected to operate the driving gear 61 which is disposed about the center 22.

Upon the rotation of the shaft 68 the control mechanism 74 is actuated through the gears 69 and 71, shaft 72 and the belt and pulley connection 73. This driving connection controls the direction of rotation of the work and effects the stopping of the machine after a predetermined cycle of operation. The operation of the shaft 68 rotates either the gear 81 or 86, as illustrated in Figs. 7 and 8 respectively, depending upon which of the clutches 85 or 88 is actuated to connect the gear to the shaft. The shaft 84 is rotated in one direction when the clutch 85 engages the gear 81 to the shaft and in the opposite direction of rotation when the clutch 88 connects the gear 86 to the shaft. In this manner the shaft 80 is operated in a clockwise or counter-clockwise direction for operating the work in one direction or the other direction by means of the belt 53 and its associated pulleys.

A clutch operating arm 95 is pivoted at 92 and has a bifurcated end portion 93 which engages a slot 94 in a collar employed for shifting the clutch elements 85 and 88 longitudinally of the shaft 68. A rod 96 is employed for rocking the lever

95 about the pivot 92 for operating the clutches 85 and 88 for effecting the driving of the shaft 84 in one or the other direction as the case may be. The lever 95 has an aperture 97 therein through which a shaft 98 extends, the aperture being elongated to permit the rocking of the lever 95 about the pivot 92 without interference by the shaft 98. The purpose of the shaft will be explained hereinafter.

The control mechanism 74 is operated by the belt and pulley 73 off of the shaft 72, which is illustrated enlarged in Fig. 5. The belt and pulley 73 drives through a pulley 101 to operate the shaft 102 which is suitably supported in bearings 103 and 104. A gear 105 is mounted on the shaft 102 which drives a gear 106 which is mounted on a stub shaft 107 for rotation about the shaft 102 on bearings 108 and 109. The gear 106 is meshed with two internal gears, fixed gear 110 and a rotatable gear 111 having an odd number of teeth, for example, the internal gear 110 may have 89 teeth while the internal gear 111 may have 79 teeth to cause the gear 111 to be advanced one tooth during one complete rotation of the gear 106 about the shaft 102. This differential construction provides a very slow movement to the gear 111 relative to the rotation of the shaft 102 thereby effecting a slow movement of the shift cams 100 and 112 which are mounted on the support 113 of the gear 111 and the stop elements 114 which are likewise carried by the body portion 113 through the supporting annular member 115.

In Fig. 9, I have shown an enlarged sectional view of a portion of the control mechanism illustrated in Fig. 4, wherein through the rocking of a handle 116 the shaft 117 is rotated for moving the clutch shifting rod 96 longitudinally of its length. A projection 118 is mounted on an arm which projects upwardly from the shaft 117 and is disposed in the path of movement of the shift cams 100 and 112 for rocking the shaft 117 first in one direction and then in another through the engagement of the cams 100 and 112 therewith. Any number of the elements 100 and 112 may be disposed about the body portion 113 spaced any distance apart for controlling the length of time between each reversal or shifting of the rod 96.

In a similar manner, any number of stop elements 114 may be disposed about the member 115 to control the stopping of the machine after a predetermined number of alternations of the work. The stop elements 114 engage the extending arm 121, as illustrated in Fig. 4, for operating a stop lever 122 to press a button 123 of the electric switch 124 for cutting off the current to the motor to stop the operation of the machine. A start lever 125 is likewise pivoted to the side of the machine having a projecting element in engagement with a start button 126 of the switch for starting the machine upon the actuation of the lever 125.

For controlling the degree of reciprocation of the table 18 and for effecting such reciprocation, the ring gear 78 is mounted on a shaft 127 for effecting the rotation of a gear 128 which is meshed with a large gear 129 supported on a hollow shaft 131 through which the rod 98 extends. During the operation of the machine and the rotation of the ring gear 78, the gear 129 is driven in rotation. The side of the gear is provided with a dove tail slot 132 in which a dove tailed arm 133 is mounted having a pin 134 thereon which engages a link 130 pivoted at 135 to a lever 136 which is pivotally mounted on a shaft 137 through a

boss 138. The upper end of the lever 136 is pivoted by a pin 139 to a link 141 which is pivoted at 142 to the table 18. Upon the rotation of the gear 129 the adjustable pivot point 134 is rotated about the shaft 131 to carry the link 130 around therewith to cause the lever 136 to be oscillated about the pivot 137 to move the link 141 substantially longitudinally through a small arc which, owing to its pivotal connection to the table 18, causes the table to be reciprocated on the ways 17.

Referring to Fig. 4, it will be noted that the shaft 98 carries a beveled pinion 143 in engagement with a beveled gear 144 which gear is mounted for rotation in fixed position to operate a lead screw 145 which is carried by the dovetailed arm 133 and which, upon rotation of the beveled gears 143 and 144, causes the lead screw and therefore the dovetailed arm 133 to be moved radially of the gear 129. In this manner the position of the pivot 134 relative to the central axis of the gear 129 may be adjusted exteriorly of the machine. By adjusting the pivot in this manner the degree of oscillation of the lever 136 and, therefore, the amount of reciprocation to the table 18 is regulated from zero to an amount at least as great as the width of the tools 24. The object of reciprocating the table is to produce uniform wear across the surface of the tools and to increase the amount of machining lengthwise of the teeth. It will be noted that the shaft 98 extends out from the machine, above the motor and the arrows thereabove indicate the direction the shaft is to be turned to shorten or lengthen the stroke.

When a series of like gears are to be finished, the control mechanism is first adjusted to effect the required amount of machining, that is to say, the number of rotations in one direction are set and the number of rotations in a reverse direction and the number of times the cycle is repeated before the machine is to be stopped. Thus prearranged adjustment is effected through the setting of the shift blocks 100 and 112 and the stop element 114. In this manner all of the gears will be treated exactly alike which is desirable for like gears, the desired number of operations to complete a cycle is found empirically and will be substantially known from prior operation of the machine. After the "start" lever is pushed to throw the switch, the gear and tools will operate a predetermined number of times in rotation in one direction during a relative reciprocation therebetween after which they may be reversed and run in the opposite direction and the cycle repeated a predetermined number of times until the stop element is automatically moved to throw the switch to off position to stop the operation of the machine. Thereafter the handle 43 is moved upwardly and the spindle 49 and the center 23 are moved away from the gear shaft to permit the gear to be removed and a new gear disposed in clamped relation to the centers. The handle 43 is then moved downwardly to move the raised tool into engagement with the gear and to provide a pressure between the gear and tools and it is only necessary to again move the "start" lever to have the cycle of operation repeated to effect a complete machining of the gear.

As has been pointed out hereinabove, the tools may be angularly disposed an amount equal to the angle of the gear teeth when a spiral gear is to be machined or when spiral tools are utilized and a spur gear to be machined, the tools may

be set off an amount equal to the angle of the tool teeth, to produce a uniform surface throughout the length of the gear teeth. The tools may be offset slightly from such true angular relation to produce a wear on either or both side edges of the teeth, of the shape and form of the teeth but of slightly less width, to permit the meshing of the teeth without interference when they are shifted longitudinally of each other into and out of mesh. The supports for the tools are such that they may be readily set off at any angle so that this particular method of machining gears to have the relief at the side edges of the teeth is quite practical. It is to be understood that a suitable lapping compound is disposed between the laps and the gears which may be applied in any manner, either manually or when of sufficient fluidity by a pumping system during the operation of the machine. The laps are made of cast iron or other metal well known for its resistance to wear in the presence of the lapping compound.

It is to be understood that, when desirable, the lapping compound can be entirely omitted and a burnishing operation effected by the machine and also, when desirable, gear like cutting tools as illustrated and described in my copending application, Serial No. 588,635, filed January 25, 1932, and assigned to the assignee of the present invention, may be employed for shaving the teeth to accurate predetermined dimensions. The present machine, therefore, is not limited to a lapping operation, as primarily disclosed in the present description, but is equally effective for producing a burnishing operation and also a shaving operation when burnishing and/or shaving tools are substituted for the lapping tools.

While I have illustrated and described but a single embodiment of my invention, it will be apparent to those skilled in the art that various changes, omissions, additions and substitutions may be made therein without departing from the spirit and scope of my invention, as set forth in the accompanying claims.

I claim as my invention:

1. The combination in a gear lapping machine for finishing gears after hardening, of a reciprocable table for supporting a gear to be lapped, a yoke bridging said table, a plurality of pivotally mounted spindles on said yoke, gear-like lapping tools mounted on said spindles having teeth mated with the teeth of said gear and mounted for rotation in different planes which are disposed at an angle to the axis of the gear, means for rotating the gear for driving said lapping tools, and means for reciprocating said table during said gear rotation.

2. The combination in a gear lapping machine for finishing gears after hardening, of a reciprocable table for supporting a gear to be lapped on an axis about which the gear rotates, a yoke bridging said table, a plurality of pivotally mounted spindles on said yoke, gear-like lapping tools mounted on said spindles having teeth mated with the teeth of said gear, said tools operating in different planes which are disposed at an angle to the axis of said gear, means for rotating the gear for driving said lapping tools, means for reciprocating said table during said gear rotation, and means for reversing the rotation of said gear a predetermined number of cycles.

3. The combination in a gear lapping machine for finishing gears after hardening, of means for supporting a spur gear to be lapped on an axis about which the gear rotates, a plurality of gear-

like spiral lapping tools having teeth mated with the teeth of said gear and mounted to rotate in different planes which are disposed at an angle to the axis of said gear, means for effecting the 5 rotation of the gear and said lapping tools, and means for moving one of the tools from the finished gear to permit the gear to be removed without disturbing the other tools.

4. The combination in a gear finishing machine 10 for operating on roughed out gears to machine the teeth to finished dimensions, of means for supporting a roughed out gear to be machined on an axis about which the gear rotates, a plurality of gear-like finishing tools having teeth mated 15 with the teeth of said gear and disposed to rotate in different planes and at an angle to the said axis of the gear, means for effecting the rotation of the gear relative to the finishing tools, and means for moving one of the tools away from said 20 gear without changing the adjusted position of said tool.

5. The combination in a gear finishing machine for machining the teeth of gears to finished dimensions, of a yoke, a plurality of pivotal supports on each yoke, machining tools mounted on 25 said supports, means for adjusting said supports angularly to dispose said tools in predetermined angular relation to the gear, a reciprocable table for supporting said gear in rotation in position to 30 be engaged by said tools, means for reciprocating said table, means for rotating said gear and machine tools relative to each other, automatic means for reversing the direction of rotation of said gear and tools, and means for stopping the machine 35 thereafter.

6. The combination in a device for machining the teeth of gears to finished dimensions, of means for rotatably supporting said gear, means for moving said gear axially, tool supports which 40 are angularly adjustable to have the teeth of the machine tools mate with the teeth of the gear, tools on said supports, driving means for effecting the rotation of said gear and tools, and control means for reversing said drive means a predetermined number of times and for thereafter stopping the machine.

7. The combination in a device for machining the teeth of gears to finished dimensions, of a machine bed for supporting a yoke of inverted 50 U-shape, ways on said bed, a table mounted for reciprocal movement on said ways between the legs of said yoke, means on said table for rotatably mounting a gear to be machined, a plurality of tool mounting means on said yoke which are adjustable angularly, tools on said mounting means 55 engageable with said gear to be machined, means for driving said gear and tools, and means on said machine for controlling the driving of said gear

and tool a predetermined number of cycles of operation and for stopping the machine thereafter.

8. The combination in a device for machining the teeth of gears to finished dimensions, of a machine bed for supporting a yoke of inverted U-shape, ways on said bed, a table mounted for reciprocal movement on said ways between the legs of said yoke, means on said table for rotatably mounting a gear to be machined, a plurality of tool mounting means on said yoke which are 10 adjustable angularly, tools on said means engageable with said gears to be machined, means for raising one of said supports and tools to permit the removal and insertion of said gear without changing its position of adjustment, and locking 15 means for retaining said tool in adjusted engagement with said gear.

9. The combination in a device for machining the teeth of gears to finished dimensions, of a machine bed for supporting a yoke of inverted U-shape, ways on said bed, a table mounted for reciprocal movement on said ways between the legs of said yoke, means on said table for rotatably mounting a gear to be machined, a plurality of tool mounting means on said yoke which are 20 adjustable angularly, tools on said means engageable with said gears to be machined, means for raising one of said supports and tools to permit the removal and insertion of said gear, locking 25 means for retaining said tool in engagement with said gear, and brake mechanism on each of said tool supports for applying a load to the tool.

10. The combination in a device for machining the teeth of gears to finished dimensions, of a machine bed for supporting a yoke of inverted U-shape, ways on said bed, a table mounted for reciprocal movement on said ways between the legs of said yoke, means on said table for rotatably mounting a gear to be machined, a plurality of tool mounting means on said yoke which are 30 adjustable angularly, tools on said means engageable with said gears to be machined, means for raising one of said supports and tools to permit the removal and insertion of said gear, locking 35 means for retaining said tool in engagement with said gear, and brake mechanism on each of said tool supports for applying a load to the tool.

11. A machine for finishing teeth of gears to accurate form including, in combination, a supporting bed, a reciprocable table mounted thereon, an arbor supported on said table for retaining a gear to be machined for rotational movement, a plurality of arbors pivotally mounted and positionable parallel to said gear arbor and angularly thereto and to each other, machining tools on said arbors in mated relation with said gear, and means for driving said gear in rotation and said 50 table in reciprocation.

ERNEST A. OVERSTEDT.
